Application March 16, 1959, Serial No. 55,006

Term of patent 14 years

(Cl. D58—8)

FIG. 1.

FIG. 2.

The side not shown is the same as the side shown.

The characteristic features of my design for the bottle disclosed reside in the neck and shoulder portions thereof having the configurations shown which comprise approximately one-third of the total bottle height.

I claim:

The ornamental design for a bottle, as shown and described.
